UNITED STATES PATENT OFFICE.

PETER BURT, JOSEPH SMITH BURT, TOM WOTHERSPOON BURT, JOHN WOTHERSPOON BURT, AND GEORGE PETER BURT, OF GLASGOW, SCOTLAND.

WRINGER.

Application filed May 23, 1927, Serial No. 193,574, and in Great Britain August 26, 1926.

This invention relates to improvements in wringers and aims to provide an inexpensive construction suitable for mass production, lighter, and occupying less space than wringers of the usual types.

The wringer of the invention comprises a frame constructed of metal stampings comprising vertical posts of channel form, which may each comprise a pair of channels, say of pressed steel, facing one another at each side of the frame, and a horizontal top rail of inverted channel form bridging the posts and embraced at each end by a post or embracing at each end the upper end of a post, the rail being bolted or otherwise secured to the posts.

Levers for applying pressure to the rollers may be in part accommodated in the horizontal channel rail, being fulcrumed on pivot pins penetrating the flanges of the rail.

Each post presents a guideway for sprung blocks presenting bearings for the roller journals.

In the accompanying drawings, which illustrate a wringer according to the invention, Fig. 1 is a vertical section; Fig. 2 is a side elevation; Fig. 3 is an end elevation; Fig. 4 is a fragmentary detail view to a larger scale; Fig. 5 is a fragmentary section on the line 5—5 of Fig. 4; Fig. 6 is a detail view, partly in section, at right-angles to Fig. 4; Fig. 7 is a section on the line 7—7 of Fig. 2 to a larger scale; Figs. 8 and 9 are detail views at right angles to one another.

The wringer structure shown comprises two vertical end posts, each constituted by channel members 1 facing one another and connected by bolts 2 at their top ends to a horizontal rail 3 of inverted channel section, the channel members 1 being notched at their top ends at 4 (see Fig. 6) to embrace and engage the ends of the rail 3, the upper corners of the frame thus formed being reinforced by corner pieces 5 penetrated by the bolts 2.

Pressure levers 7 of channel section are in part accommodated in the rail 3, being fulcrumed on pivot pins 8 penetrating the flanges of the rail 3, washers 9 being interposed between the sides of the levers and the flanges.

The end posts serve as guides for bearing blocks 11 partly embracing the journals 12

of the upper roller 13 parallel with the top rail 3. On top of the blocks 11 are plates 14 which bear the outer or remote ends of the levers 7. Below the blocks 11 are blocks 15 presenting bearings for the journals 16 of the lower roller 17, the blocks 15 abutting fixed plugs 19.

Welded to the lower ends of the end posts are box members 18 (see Figs. 5 and 6) to which are connected by bolts 21 cross-members 20 which complete the rigid portion of the structure.

Projecting through a slot 22 in the web of the rail 3 is a bolt 23 having at its lower end a T head 24 engaging from below a slotted buckle member 25 (see Figs. 8 and 9) the ends of which are located below and engageable with pins 26 on the inner ends of the levers 7. The shank of the bolt 23 is embraced by a helical spring 27 adapted to be compressed between a handwheel 28 in a screwthreaded engagement with the bolt and a washer 29 bearing on the web of the rail 3. The arrangement is such that the bolt may be inserted from above the rail 3, the T-head 24 being passed through the slots in the rail and in the buckle and the bolt thereafter axially rotated through 90°.

We claim:

1. In a wringer, in combination, vertical end posts formed as stampings of channel section, each post comprising a pair of channels facing one another, and notched at their top ends, a top rail formed as a stamping of inverted channel section bridging the posts and engaged by the notched ends of the posts, box members welded to the lower ends of said posts, cross members connecting said box members, rollers parallel with the top rail having end journals, bearing members for said journals accommodated in the channels presented by the posts, levers of channel section pivoted to and accommodated within the top rail and having their remote ends within the channels of the posts, and means applied to the adjacent ends of the levers for exercising pressure on the rollers.

2. In a wringer, in combination, vertical end posts formed as stampings of channel section, each post comprising a pair of channels facing one another, and notched at their ends, a slotted top rail formed as a stamping of inverted channel section bridging the posts and engaged by the notched ends of

the posts, box members welded to the lower ends of said posts, cross members connecting said box members, rollers parallel with the top rail having end journals, bearing members for said journals accommodated in the channels presented by the posts, levers of channel section pivoted to and accommodated within the top rail and having their remote ends within the channels of the posts, a slotted buckle beneath the adjacent ends of the levers, and a member penetrat-

ing the slots in the rail and in the buckle for applying upward pressure to the adjacent ends of the levers.

In testimony whereof we have signed our ¹⁵ names to this specification.

PETER BURT.

JOSEPH SMITH BURT.

TOM WOTHERSPOON BURT.
